US0D1022370S

(12) **United States Design Patent** (10) Patent No.: **US D1,022,370 S**
 Berrouard et al. (45) Date of Patent: ** Apr. 9, 2024

(54) **BRACKET FOR A TOOL**

(71) Applicant: **GARANT GP**,
 Saint-François-de-la-Rivière-du-Sud
 (CA)

(72) Inventors: **Mathieu Berrouard**, Lévis (CA); **Leïla Chouikh**, Montréal (CA)

(73) Assignee: **GARANT GP**,
 Saint-François-de-la-Rivière-du-Sud
 (CA)

(**) Term: **15 Years**

(21) Appl. No.: **29/791,955**

(22) Filed: **Feb. 22, 2022**

(51) LOC (14) Cl. **07-05**

 LLP; Gwendoline Bruneau

(57) **CLAIM**

The ornamental design for a bracket for a tool, as shown and described.

DESCRIPTION

FIG. 1 is perspective view of the new design, with an environment shown in broken lines that forms no part of the claimed design;

FIG. 2 is a front view thereof;

FIG. 3 is a rear view thereof;

FIG. 4 a first side view thereof;

FIG. 5 is a second side view thereof;

FIG. 6 is a top view thereof; and,

FIG. 7 is a bottom view thereof.

The broken lines shown in FIGS. 1-7 illustrate portions that form no part of the claimed design.

1 Claim, 4 Drawing Sheets
